FANFOLD MACHINE

Charles Butterfield, Wyoming, Ohio, assignor to
The Globe-Wernicke Company, Norwood, Ohio,
a corporation of Ohio

Application May 11, 1939, Serial No. 273,067

18 Claims. (Cl. 270—73)

This invention relates to a machine for fanfolding long lengths of paper-like material which may or may not have been previously treated in any desired manner and also to certain apparatus for treating the material prior to fanfolding.

While this machine is adaptable to numerous uses I have illustrated it specifically in connection with the manufacture of label elements such as are used in connection with file folders, said label elements consisting of strips of paper preferably coated with adhesive on one side and having a score line so that they may be folded over and adhesively secured along an edge of a file folder. Identifying marks may be printed or typed upon these strips before they are adhesively secured to the file folders and for this purpose the elements preferably bear some sort of datum point, so that a typist may align them uniformly in a typewriter.

Such labels have been in the past sold either in stacks of individual labels or in rolls of labels in which the labels were defined by frangible lines or lines of perforations so that they can be torn apart. I have found that it is desirable to provide these labels in continuous strips from which individual labels may be torn and to fanfold the strips so that they may be packed in convenient size boxes. By fanfolding I mean that a long strip is folded in a zigzag manner so that the length of material will lie flat constituting a stack, each layer of which contains a number of labels frangibly connected together and with layers connected to each other by frangible lines alternately at opposite ends thereof.

My complete machine therefore comprises a means for producing in a strip of material such as for example paper, which may be adhesively coated on one side, a series of spaced, transverse score lines and then producing thereon a series of spaced lines of perforations or frangible lines. Material is then conducted past a means which serves to emboss a datum point on each label at a predetermined position. At this point the strip constitutes a series of labels connected together by frangible lines, each label having a score line so that it may be folded and each label having embossed thereon a datum point. The machine then includes an arrangement for fanfolding this continuous strip so that the folds will occur on frangible lines, whereby each layer will contain a predetermined number of separable labels.

It is an object of my invention to provide a machine which will produce fanfolded series of labels as above outlined. It is an object of my

invention to provide specific means for producing score lines in a strip and for producing frangible lines in this strip, and for embossing a datum point on each label. It is a further object of my invention to provide means whereby the embossing means may be rendered inoperative in case there should be desired a series of labels which are not embossed.

It is another object of my invention to provide means for fanfolding a strip of paper or the like which will be relatively simple in construction and operation. More specifically, it is an object of my invention to provide a fanfolding arrangement employing suction, whereby the paper will not be in any way marked. In this connection it is an object of my invention to provide a pair of rolls between which a strip is adapted to pass, said rolls having suction orifices therein so oriented that suction will be applied to the strip alternately first on one side and then on the other, and to provide means for releasing the suction means after a predetermined interval whereby the strip will be fanfolded. It is also an object of my invention to provide means for severing the strip after a predetermined length thereof has been fanfolded. Another object of my invention is to provide means compacting a fanfolded set of labels after they have been severed from the strip. Generally speaking, it is an object of my invention to provide a complete machine which is as simple as may be, and which will automatically and continuously provide a product such as outlined above.

These and other objects of my invention which will be set forth hereinafter or will be apparent to one skilled in the art upon reading these specifications, I accomplish by that certain construction and arrangement of parts of which I shall now describe a preferred embodiment.

Reference is made to the drawings which form a part hereof, and in which:

Figure 1 is an elevational view of a machine according to my invention.

Fig. 2 is a plan view of the same.

Fig. 3 is an end elevation of the same viewed from the left of Fig. 1.

Fig. 4 is an elevational view of the machine from the other side of Fig. 1.

Fig. 5 is a cross sectional view taken on the line 5—5 of Fig. 3.

Fig. 6 is a cross sectional view taken on the line 6—6 of Fig. 5.

Fig. 7 is a detailed partial perspective view of the product of the machine.

Fig. 8 is a detailed perspective view of an insert for the fanfolding rolls as viewed from the inside.

Briefly in the practice of my invention and referring particularly to Fig. 5, I provide means generally indicated at A for forming in a strip of paper or the like indicated at 10, a series of spaced, transverse score lines indicated at 11 in Fig. 7. The strip passes from the point A to the point B where I have provided means for producing in the strip transverse lines of perforation or frangible lines indicated at 12 in Fig. 7. At C I have provided means for producing in the strip a series of spaced indentations or datum points indicated at 13 in Fig. 7. At D I provide means for transmitting driving force to the strip of material and at E I provide a fanfolding means and strip severing means. The fanfolded strip falls through a hopper generally indicated at 14 and drops into a box 15 which may be the box in which the fanfolded labels are to be ultimately packaged.

At A I have shown a pair of cooperating rolls 16 and 17. The roll 16 is keyed to a shaft 18 and carries the spaced scoring knives 19 which are arranged around the circumference thereof and parallel to the axis of the roll. The roll 16 is adjustable in relation to the roll 17 in any desired manner as for example by means indicated generally at 20, the bearings of the roll 16 indicated at 21 being mounted for vertical sliding movement as shown and being urged upwardly by means of a spring 22. The roll 17 is keyed upon a shaft 23 and is provided with a rubber surface 24.

At station B I have provided a pair of rolls 25 and 26. The roll 25 is adjustably mounted in a manner similar to roll 16. This mounting therefore will not be described further. The roll 25 carries a series of perforating elements 27 which are disposed around the periphery thereof parallel to the axis of the roll. The roll 26 is non-adjustably mounted and is metallic, as for example, of steel.

At station C I provide a knee roll 28 which may be of any desired material, as for example, steel, and which has bolted to one end thereof as by means of the bolts 29, a fiber disc 30. The heads of the bolts 29 engage a metallic cover plate 31 which holds the fiber disc 30 in place. Directly above the fiber disc 30 I mount a wheel 32 provided with embossing elements 33 about its periphery. As will be clear from Figs. 2 and 5, the wheel 32 is mounted by means of a stub shaft 34 on a link 35 which is pivoted as at 36, to a bracket 37 on the machine frame. A spring 38 tends to urge the wheel 32 upwardly and the position of the wheel 32 with respect to the fiber disc 30 may be adjusted as by means of a bolt 39 threaded through a part of the machine frame as at 40 and bearing, as at 41, against the link 35. A lock nut 42 may be provided for locking the wheel 32 in any position of adjustment.

Cooperating with the roll 28 is a roll 43 which is adjustably mounted similar to the rolls 16 and 25 and therefore the mounting will not be described further. The rolls 28 and 43 cooperate to transmit driving force to the strip whereas the cooperating rolls 16, 17, 25, 26, and the wheel 32 and disc 30 are merely driven in timed relation to the strip but exert no driving force thereon.

From the rolls 28, 43, the strip passes downwardly to the fanfolding station E. The fanfolded portion of the apparatus comprises a pair of

rolls 44 and 45 which are in most respects identical.

In view of the fact that the mountings of the two rolls are for the most part identical I shall describe only one, it being understood that insofar as only one is described, the description applies equally well to the other. Referring particularly to Figs. 5 and 6, it will be observed that the rolls are mounted upon shafts 46 having a bearing at 47. At this point one difference in the mounting becomes apparent in that the shaft 46 of the roll 45 is mounted in a bearing block 48 which is movable in relation to the roll. The shaft 46 of the roll 44 has a fixed bearing as at 49. The purpose of the movable bearing block 48 will be pointed out more clearly hereinafter. The shaft 46 is bored out for a considerable depth and has a bearing upon a reduced portion 50 of a shaft 51. The shaft 51 for the roll 45 is adjustably mounted in the same manner as the shaft 46 of the roll 45. The shaft 51 of the roll 45 is non-rotatably mounted in a bearing block 48' which bearing block is adjustable in the same manner as the bearing block 48. The shaft 51, of the roll 44 is non-rotatably mounted in the machine frame as indicated at 52. The rolls 45 and 44 are respectively keyed to their shafts 46 so as to rotate therewith.

The shafts 51 have a central bore 53 and in the reduced portion 50 thereof are provided the slots 54, communicating with the bore 53. The rolls 44 and 45 are provided with the radial bores 55 and in the particular instance shown it will be noted that the bores 55 are disposed in groups of two, diametrically opposed to each other. Dovetailed slots 56 are provided adjacent the surface of the rolls 44 and 45, within which are mounted the manifold blocks 57 shown more in detail in Fig. 8. Upon the under surface of the blocks 57 is a slot 58 which when the block is in position on the roll is adapted to communicate with the bores 55, and a series of suction orifices 59 are provided communicating with the manifold or slot 58. The bore 53 at the frame end of the shaft 51 is in communication with a valve 60 connected to a suction line 61. From this description it will be clear that as the rolls 44 and 45 rotate, the bores 55 will be in communication with the slots 54 during one counter revolution, and that if the valve 60 is opened during this counter revolution suction will be exerted through the perforations or suction orifices 59. In this connection means are provided which will be described hereinafter for actuating the valve 60 in timed relation to the rotation of the rolls.

It will be noted that the roll 45 has a flat portion 62 in which there is a slot 63 for the purpose of mounting a cutter 64. In the particular instance shown, the cutter 64 is held in place by means of a depressed block 65 and a bolt 66 threaded into the roll 45. It will be noted that the cutting edge of the cutter 64 projects very slightly beyond the periphery of the roll.

The movable mounting of the roll 45 was generally discussed above. It will be noted that springs 67 are provided for normally urging the bearing blocks 48 and 48' to the right in Fig. 6 so as to leave a space 68 between the rolls. The width of the space 68 may be controlled by means of an arrangement comprising plunger elements 69 bearing respectively against the blocks 48 and 48', the plungers 69 having bearings in brackets 70 of the machine frame so as to limit the outward movement of the bearing blocks 48 and 48'. 75

Adjusting screws 71 threaded into links 72, which will be described hereinafter, are provided for reducing the limit of movement toward the right in Fig. 6. The adjustment may be fixed by means 5 of lock nuts 73.

The arrangement of the parts just described is such that as the rolls 44 and 45 rotate they are spaced slightly apart so that the cutting edge 64 will not cut the material and the rolls 44 and 45 10 are angularly so oriented that a series of suction orifices 59 will be presented to the strip alternately from one side and then the other. With reference to Fig. 5, the suction orifices 59 of the roll 44 have exerted suction on the strip 10 and 15 have carried the strip partially around the roll 44 through substantially a quadrant of revolution. At this point the means which will be described hereinafter will become operative to cut off the suction on the roll 44 and to produce suction in 20 the roll 45. As shown in Fig. 5, the suction orifices 59 of the roll 45 are in a position where when suction is exerted they will serve to carry the strip partially around the roll 45.

In order to perfect the fan folding I have provided rollers 74 mounted upon pivotal brackets 75 attached to the machine frame as at 76. The rolls 74 do not engage respectively the rolls 44 and 45 but are spaced slightly therefrom and serve to fold the strip as shown at the left side of Fig. 5. 30 The rolls 74 do not need to touch their respective fanfolding rolls because the fold will be produced along lines of perforations.

Although means are provided for cutting off the suction after the strip has been carried around 35 a roll for substantially a quadrant of revolution there may be a tendency for the strip to be carried further around due to inertia or other causes, and I have therefore provided the stop blades 77 which limit the distance around the rolls to which 40 the strip may be carried.

In order to sever the strip after a predetermined length thereof has been fanfolded I provide means for causing the roll 45 to approach the roll 44 to a point where the cutter 64 will produce as it 45 rotates a cut. These means include a link 78 pivoted upon a shaft 79 and carrying a cam roller 80 in operative relationship with a cam 81. The cam 81 is fixed upon a shaft 82 which is driven in timed relation with the remainder of the apparatus. The shaft 79 carries fixed upon it the 50 downwardly depending links 72 described above, and it will be clear that when the rise 83 of the cam 81 produces a clockwise movement of the link 78 this movement will be transmitted to the links 72 and the roll 45 will be caused to approach the roll 44.

Also mounted upon the shaft 82 is a cam 84 having a rise 85. This cam is in operative relationship with a push rod 86 mounted in any desired manner on the machine frame and connected to the plunger of a valve 87. The valve 87 is in a compressed air line 88 and controls the flow of air to the nozzle 89. The cams 81 and 84 are so oriented that substantially at the instant, or 65 very shortly after, the cam 81 has become operative to cause the cutter 64 to sever the strip the cam 84 will actuate the valve 87, causing a blast of air from the nozzle 89. This blast of air tends to compact the fanfolded, severed strip which 70 otherwise would tend to settle rather slowly into the receptacle 15.

Referring to Fig. 1 it will be seen that the valves 60 are arranged to be actuated by the links 90 under the action of the tension springs 91. The 75 links 90 are pivoted at 92 and are provided with

cam rollers 93 which are acted upon by cams 94 which are identical except that they are angularly displaced by 180°. It will be clear from Fig. 1 that as the cam roller 93 of a link 90 approaches the drop 95 in a cam 94, the respective spring 91 5 will act upon the respective link 90 and cause actuation of the valve. The cams 94 are so disposed that each valve 60 will become operative when one set of suction orifices 59 of its respective roll is in a position to contact the strip and 10 when its bores 55 come into communication with the ports 54. Similarly when the rollers 93 are acted upon by the rise 96 of the cams 94 the respective valves 60 will be closed so as to cut off the suction and release the strip. 15

The general aspects of the machine are best illustrated in Figs. 1 to 4 inclusive. It will be seen that the strip from which the fanfolded elements are made is provided in roll form as at 97, the roll being carried in any convenient bracket 98. Power is applied to the machine by means of a pulley 99 and a belt 100. The pulley 99 is mounted upon a shaft 101 which carries also a pinion 102. The pinion 102 meshes with a gear 103 carried on the shaft 104. The gear 103 meshes 20 with the gears 105, 106 and 107, which are mounted respectively upon the shafts 23, 108 and 46. These shafts respectively carry the rolls 17, 26 and 44. The gears mesh with gears 109 and 110 mounted respectively upon the shafts 18 and 111 30 upon which are mounted respectively the rolls 16 and 25. The gear 107 meshes with the gear 112 mounted upon the shaft 46 which carries the roll 45. The rolls 28 and 43 are driven by means of gears 113 and 114 mounted upon the same 35 shafts as the rolls, the gears 113 and 114 intermeshing and power being transmitted to the gear 113 from the gear 106 by means of the idler pinion 115. The shaft 46 of the roll 45 carries also a worm 116 which is in driving relationship with a worm wheel 117 mounted upon a shaft 118 which is carried in a bearing 119. Upon the other end of the shaft 118 is mounted a miter gear 120 which is in driving relationship with a mitre gear 121 mounted upon the shaft 88 which 45 carries the cams 81 and 84.

In Fig. 1 I have shown a hopper 122 through which receptacles 15 may be inserted for filling and removed when they are full.

It will be understood that numerous modifications of this apparatus will occur to those skilled in the art and that such modifications may be made without departing from the spirit of my invention. I therefore do not intend to limit myself in any manner whatsoever except as specifically pointed out in the claims which follow. 50

Having now fully described my invention, what I claim as new and desire to secure by Letters Patent is:

1. Apparatus for fanfolding paper-like material fed thereto as from a roll, comprising a pair of rolls between which said material passes, means on said rolls respectively, operable on said material alternately to cause said material to be carried partially around one roll and then partially around the other, means cooperating with each of said rolls respectively for folding back against such roll that portion of the material which has previously been carried partially around the other of said rolls, and means for rendering inoperative alternately said first mentioned means when said material has been carried around said rolls respectively a predetermined distance. 65

2. Apparatus for fanfolding paper-like mate- 70

75

rial fed thereto as from a roll, comprising a pair of rolls between which said material passes, means on said rolls respectively, operable on said material alternately to cause said material to be carried partially around one roll and then partially around the other, means cooperating with each of said rolls respectively for folding back against such roll that portion of the material which has previously been carried partially around the other of said rolls, and means for rendering inoperative alternately said first mentioned means when said material has been carried around said rolls respectively a predetermined distance, and stop means positioned in operative relationship with the respective rolls to act upon the folded edges of the material to prevent said material from being carried on around said rolls.

3. Apparatus for fanfolding paper-like material fed thereto as from a roll, comprising a pair of rolls between which said material passes, one of said rolls being movable toward the other, but normally held spaced therefrom a slight amount, said movable roll carrying a cutting element positioned to extend slightly beyond the periphery of the roll whereby it will not normally perform a cutting action on the material, means on said rolls respectively, operable on said material alternately to cause said material to be carried partially around one roll and then partially around the other, means for rendering inoperative alternately said first mentioned means when said material has been carried around said rolls respectively a predetermined distance, and means operative when a predetermined length of said material has been fanfolded, for moving said movable roll toward the other, whereby to render said cutting edge operative.

4. Apparatus for fanfolding paper-like material fed thereto as from a roll, comprising a pair of rolls between which said material passes, one of said rolls being movable toward the other, but normally held spaced therefrom a slight amount, said movable roll carrying a cutting element positioned to extend slightly beyond the periphery of the roll whereby it will not normally perform a cutting action on the material, means on said rolls respectively, operable on said material alternately to cause said material to be carried partially around one roll and then partially around the other, means cooperating with each of said rolls respectively for folding back against such rolls that portion of the material which has previously been carried partially around the other of said rolls, means for rendering inoperative alternately said first mentioned means when said material has been carried around said rolls respectively a predetermined distance, and means operative when a predetermined length of said material has been fanfolded, for moving said movable roll toward the other, whereby to render said cutting edge operative.

5. Apparatus for fanfolding paper-like material fed thereto as from a roll, comprising a pair of rolls between which said material passes, one of said rolls being movable toward the other, but normally held spaced therefrom a slight amount, said movable roll carrying a cutting element positioned to extend slightly beyond the periphery of the roll whereby it will not normally perform a cutting action on the material, means on said rolls respectively, operable on said material alternately to cause said material to be carried partially around one roll and then partially around the other, means cooperating with each of said

rolls respectively for folding back against such rolls that portion of the material which has previously been carried partially around the other of said rolls, means for rendering inoperative alternately said first mentioned means when said material has been carried around said rolls respectively a predetermined distance, and means operative when a predetermined length of said material has been fanfolded, for moving said movable roll toward the other, whereby to render said cutting edge operative, and stop means positioned in operative relationship with the respective rolls to act upon the folded edges of the material to prevent said material from being carried on around said rolls.

6. In a fanfolding apparatus, a pair of composite shafts each comprising a non-rotatable portion and a rotatable portion, said rotatable portion having a bearing on said non-rotatable portion of each shaft having an axial bore, and a port in that portion thereof which serves as a bearing for the rotatable portion, said rotatable portion and said roller on each shaft having a bore positioned to communicate with said port intermittently as said roller rotates, a manifold disposed axially of each of said rollers adjacent the surface thereof, and a plurality of orifices in the surface of each roller communicating with said manifold, and means for applying suction at timed intervals to the bores in said shafts while said bores and ports are in communication, said rollers being oriented so that the suction orifices of the respective rollers alternately come into operative relation with a strip of material passing therebetween.

7. In a fanfolding apparatus, a pair of composite shafts each comprising a non-rotatable portion and a rotatable portion, said rotatable portion having a bearing on said non-rotatable portion and carrying a roller, one of said composite shafts being mounted for movement toward and away from the other, but normally urged away so as to leave a slight space between rollers, the non-rotatable portion of each shaft having an axial bore, and a port in that portion thereof which serves as a bearing for the rotatable portion, said rotatable portion and said roller on each shaft having a bore positioned to communicate with said port intermittently as said roller rotates, a manifold disposed axially of each of said rollers adjacent the surface thereof, and a plurality of orifices in the surface of each roller communicating with said manifold, and means for applying suction at timed intervals to the bores in said shafts while said bores and ports are in communication, said rollers being oriented so that the suction orifices of the respective rollers alternately come into operative relation with a strip of material passing therebetween, said movable roll carrying a cutting edge positioned to extend slightly beyond the surface of the roll whereby it will not normally perform a cutting action on the material, and means operative when a predetermined length of said material has been fanfolded, for moving said movable roll toward the other, whereby to render said cutting edge operative.

8. In a fanfolding apparatus, a pair of composite shafts each comprising a non-rotatable portion and a rotatable portion, said rotatable portion having a bearing on said non-rotatable portion and carrying a roller, the non-rotatable portion of each shaft having an axial bore, and a port in that portion thereof which serves as

- 1 a bearing for the rotatable portion, said rotatable portion and said roller on each shaft having a bore positioned to communicate with said port intermittently as said roller rotates, a manifold disposed axially of each of said rollers adjacent the surface thereof, and a plurality of orifices in the surface of each roller communicating with said manifold, and means for applying suction at timed intervals to the bores in said shafts while

5 said bores and ports are in communication, said rollers being oriented so that the suction orifices of the respective rollers alternately come into operative relation with a strip of material passing therebetween, the means for applying suction

10 comprising a vacuum tank, a connection therefrom to the bores in said shafts and valves in said connections, cams for actuating said valves, and means for driving said cams in timed relation to the rotation of said rollers.

15 9. In a fanfolding apparatus, a pair of composite shafts each comprising a non-rotatable portion and a rotatable portion, said rotatable portion having a bearing on said non-rotatable portion and carrying a roller, one of said composite shafts being mounted for movement toward and away from the other, but normally urged away so as to leave a slight space between rollers, the non-rotatable portion of each shaft having an axial bore, and a port in that portion

20 30 thereof which serves as a bearing for the rotatable portion, said rotatable portion and said roller on each shaft having a bore positioned to communicate with said port intermittently as said roller rotates, a manifold disposed axially of each of said rollers adjacent the surface thereof, and a plurality of orifices in the surface of each roller communicating with said manifold, and means for applying suction at timed intervals to the bores in said shafts while said bores and

25 35 40 45 50 ports are in communication, said rollers being oriented so that the suction orifices of the respective rollers alternately come into operative relation with a strip of material passing therebetween, said movable roll carrying a cutting edge positioned to extend slightly beyond the surface of the roll whereby it will not normally perform a cutting action on the material, and means operative when a predetermined length of said material has been fanfolded, for moving said movable roll toward the other, whereby to render said cutting edge operative, said last mentioned means including a cam driven in

55 60 65 70 75 timed relation with the rest of the apparatus.

10. Apparatus for fanfolding paper-like material fed thereto as from a roll, comprising a pair of rolls between which said material passes, and means on said rolls respectively, operable on said material alternately to cause said material to be carried partially around one roll and then partially around the other, and means for rendering inoperative alternately said first mentioned means when said material has been carried around said rolls respectively a predetermined distance, and means for severing said material when a predetermined length thereof has been fanfolded, and means for applying a blast of air to said fanfolded elements after said material has been severed to cause them to be compacted.

11. In a fanfolding apparatus, a pair of composite shafts each comprising a non-rotatable portion and a rotatable portion, said rotatable portion having a bearing on said non-rotatable portion and carrying a roller, one of said composite shafts being mounted for movement toward and away from the other, but normally

75 urged away so as to leave a slight space between rollers, the non-rotatable portion of each shaft having an axial bore, and a port in that portion thereof which serves as a bearing for the rotatable portion, said rotatable portion and said roller on each shaft having a bore positioned to communicate with said port intermittently as said roller rotates, a manifold disposed axially of each of said rollers adjacent the surface thereof, and a plurality of orifices in the surface of each roller communicating with said manifold, and means for applying suction at timed intervals to the bores in said shafts while said bores and ports are in communication, said rollers being oriented so that the suction orifices of the respective rollers alternately come into operative relation with a strip of material passing therebetween, said movable roll carrying a cutting edge positioned to extend slightly beyond the surface of the roll whereby it will not normally perform a cutting action on the material, and means operative when a predetermined length of said material has been fanfolded, for moving said movable roll toward the other, whereby to render said cutting edge operative, and means for applying a blast of air to said fanfolded elements after said material has been severed to cause them to be compacted.

12. In a fanfolding apparatus, a pair of composite shafts each comprising a non-rotatable portion and a rotatable portion, said rotatable portion having a bearing on said non-rotatable portion and carrying a roller, one of said composite shafts being mounted for movement toward and away from the other, but normally urged away so as to leave a slight space between rollers, the non-rotatable portion of each shaft having an axial bore, and a port in that portion thereof which serves as a bearing for the rotatable portion, said rotatable portion and said roller on each shaft having a bore positioned to communicate with said port intermittently as said roller rotates, a manifold disposed axially of each of said rollers adjacent the surface thereof, and a plurality of orifices in the surface of each roller communicating with said manifold, and means for applying suction at timed intervals to the bores in said shafts while said bores and ports are in communication, said rollers being oriented so that the suction orifices of the respective rollers alternately come into operative relation with a strip of material passing therebetween, said movable roll carrying a cutting edge positioned to extend slightly beyond the surface of the roll whereby it will not normally perform a cutting action on the material, and means operative when a predetermined length of said material has been fanfolded, for moving said movable roll toward the other, whereby to render said cutting edge operative, and means for applying a blast of air to said fanfolded elements after said material has been severed to cause them to be compacted.

13. In combination in an apparatus of the class described, means for feeding a strip of paper-like material, means for operating upon said strip, means for fanfolding said strip comprising a pair of rollers between which the strip passes, means for carrying said strip alternately partially around one roll and then partially around the other, means for severing said strip after a predetermined length thereof has been fanfolded

and means for driving all of said means in timed relation.

14. In combination in an apparatus of the class described, means for feeding a strip of paper-like material, means for operating upon said strip, means for fanfolding said strip comprising a pair of rollers between which the strip passes, means for carrying said strip alternately partially around one roll and then partially around 10 the other, means for severing said strip after a predetermined length thereof has been fanfolded, means for compacting the severed material, and means for driving all of said means in timed relation.

15. 15. In combination in an apparatus of the class described, means for feeding a strip of paper-like material, means for scoring said strip, means for perforating said strip, means for embossing said strip, means for fanfolding said strip comprising 20 a pair of rollers between which the strip passes, and means for causing said material to be carried alternately partially around one roll and then partially around the other, means for severing said strip after a predetermined length thereof 25 has been fanfolded, means for compacting the severed portions of said strip and means for driving all of said means in timed relation.

16. Apparatus for producing long lengths in fanfolded condition of separable foldable elements 30 having datum points thereon from a roll of paper-like material, comprising a pair of cooperating rolls having means for forming score lines transversely of a strip led therebetween, a pair of cooperating rolls having means for forming lines 35 of perforations transversely of a strip led therebetween, a pair of cooperating rolls through which said strip is led, having means for embossing a datum point on each element between said lines of perforations, a pair of cooperating 40 rolls for transmitting driving force to said strip, and a pair of folding rolls between which said strip passes, said folding rolls each having two series of suction orifices diametrically opposed, and said rolls being oriented so that the suction orifices on said pair of rolls are in operative 45 relation with the strip passing therethrough alternately, means for supplying suction to said suction orifices, and timing means for causing said suction orifices on the respective rolls to apply 50 suction to the strip alternately on one side and then the other, whereby said strip is fanfolded, and means for severing said strip when a predetermined length thereof has been fanfolded.

17. Apparatus for producing long lengths in 55 fanfolded condition of separable foldable elements having datum points thereon from a roll of paper-like material, comprising a pair of cooperating rolls having means for forming score lines transversely of a strip led therebetween, a pair of co-

operating rolls having means for forming lines of perforations transversely of a strip led therebetween, a pair of cooperating rolls through which said strip is led, having means for embossing a datum point on each element between 5 said lines of perforations, a pair of cooperating rolls for transmitting driving force to said strip, and a pair of folding rolls between which said strip passes, said folding rolls each having two 10 series of suction orifices diametrically opposed, and said rolls being oriented so that the suction orifices on said pair of rolls are in operative relation with the strip passing therethrough alternately, means for supplying suction to said suction orifices, and timing means for causing said suction orifices on the respective rolls to apply suction to the strip alternately on one side and then the other, whereby said strip is fanfolded, means for severing said strip when a predetermined 15 length thereof has been fanfolded, and means for applying a blast of air to said fanfolded elements after said strip has been severed, to cause them to be compacted.

18. In a fanfolding apparatus a pair of composite shafts, each comprising a non-rotatable portion and a rotatable portion, said rotatable portion having a bearing on said non-rotatable portion and carrying a roller, one of said composite shafts being mounted for movement toward and away from the other but normally urged 20 away so as to leave a slight space between rollers, the non-rotatable portion of each shaft having an axial bore and a port in that portion thereof which serves as a bearing for the rotatable portion, said rotatable portion and said roller on each 25 shaft having a bore positioned to communicate with said bore intermittently as said roller rotates, a manifold disposed axially of each of said rollers adjacent the surface thereof and a plurality of orifices in the surface of each roller communicating with said manifold, means for applying suction at timed intervals to the bores in said 30 shafts while said bores and ports are in communication, said rollers being oriented so that the suction orifices of the respective rollers alternately 35 come into operative relationship with a strip of material passing therebetween, said movable roll carrying a cutting edge positioned to extend slightly beyond the surface of the roll whereby it will not normally perform a cutting action on 40 the material, means operative when a predetermined length of said material has been fanfolded, for moving said movable roll toward the other, whereby to render said cutting edge operative, 45 means for compacting the severed portion of said material, and means for driving all of said means in timed relationship.

CHARLES BUTTERFIELD.
